DEVICE FOR MEASURING LIQUIDS

Louis Jules Adrien Cadet, Le Vesinet, France, assignor to Société Anonyme dite: Société d'Etude de Distributeurs Automatiques S. E. D. A., Paris (Seine), France

Application July 22, 1937, Serial No. 155,098
In France October 8, 1936

1 Claim. (Cl. 73—247)

Known apparatus for measuring liquids of the so-called "continuous meter" type, are constituted, substantially, by a plurality of identical pistons arranged, according to a known method at equal angular distances apart relatively to each other, about a central shaft, these pistons effecting equal strokes.

In the known apparatus the movement of the pistons is controlled by a rotary distributor moving against a port face. With the known apparatus, for a comparatively small output, the resistant torque offered by the distributor, that is to say, the stress pressing the distributor on its port face is very slight with the result that the fluid-tightness of the distributor is ineffective for these small outputs. Moreover, in the case of increasing output, the stress forcing the distributor on its port face increases rapidly with the resultant danger of jamming.

According to the present invention the stress applying the distributor to its port face is so regulated as to be considerable even for very small outputs so that the fluid-tightness is effectively maintained. For increasing output to a predetermined value, the stress decreases slowly to a predetermined point from which it increases gradually in a comparatively slow manner to insure high output without the risk of jamming.

In the accompanying drawing wherein an approved embodiment of the invention is illustrated:

Figure 1 is a vertical sectional view through a measuring device constructed in accordance with the invention.

Figure 2 is a diagram showing the curve of the resistant torque of the distributor.

The measuring apparatus comprises a plurality of pistons 1^a—(1^b—1^c—1^d) actuating, through connecting rods 9^a and cranks 10^a, a shaft 2. On this shaft is rigidly secured the rotary distributor 5, which comprises an inlet opening 6 and an outlet opening 7 and which moves on a port face provided with a series of ports 8^a (8^b—8^c—8^d) corresponding to each of the pistons 1^a (1^b—1^c—1^d). The liquid is admitted through the connecting branch 3 and issues through the connecting branch 4 in the crank case.

The compensation device constructed according to the invention comprises a piston 11 moving in a cylinder 12 in communication, at its lower part, with the incoming liquid through the medium of a conduit, 11X, connecting the orifices 13 and 13'. At its upper part, the piston 11 is exposed to the pressure of the outgoing liquid through an orifice 11y. Under the effect of the

difference of pressure represented by P between the inlet and outlet for the liquid, this piston compresses a coil spring 14 taking a bearing, on the other hand, on the shoulder 15 of a member directly pressed against the shaft 2 and forming a foot step bearing. The spring 14 possesses a certain initial tension R, the increase in the force of the spring 14 due to compression by the piston 11 being too small to warrant consideration in the following equation. The downward stroke of piston 11 is limited by an abutment 16 and its upward stroke is limited by a second abutment 17 forming one piece with the shoulder 15. The piston 11 bears against this latter abutment 17 when the pressure P reaches a value P₁ which depends, of course, on the cross section of the piston 11 and on the initial tension R of the spring 14.

Assuming that S represents the value of the useful surface of the distributor 5 on which the pressure difference P is effectively exerted and that s represents the surface of piston 11, the resulting stress on shaft 2, of the distributor, is equal:

For the values of P lower than P₁;
To R—PS decreasing when P increases, and for the values of P higher than P₁;

To P (s—S) increasing with P if s is given a value higher than that of S.

In Fig. 2, the curve of the resistant torques of the distributor is indicated at E F, G, the point Co on the abscissae Po corresponding to the starting of the meter.

What I claim as my invention and desire to secure by Letters Patent is:

In a continuous meter, comprising: cylinders, pistons in these cylinders, a shaft driven by the combined action of said pistons, an inlet pipe line for the liquid, an outlet pipe line for the liquid, a distributor in the shape of a cup fast on said shaft, the convexity of this cup being turned towards the outgoing liquid and the incoming liquid tending to unseat the distributor, an auxiliary cylinder, an auxiliary piston in the auxiliary cylinder, connecting branches for connecting the two chambers of the auxiliary cylinder on opposite sides of the auxiliary piston with the incoming and outgoing liquid on opposite sides of the distributor, an abutment in said cylinder engaging said shaft, a calibrated spring taking a bearing on the auxiliary piston and pressing said abutment against the shaft of the meter to press the distributor toward its seat.
